J. G. MACLAREN

SPACING DEVICE FOR PNEUMATIC DISPATCH SYSTEMS

Original Filed March 26, 1920

Inventor
J. G. MacLaren

By Roberts, Roberts & Cushman
Notary

UNITED STATES PATENT OFFICE.

JAMES G. MACLAREN, OF SYRACUSE, NEW YORK, ASSIGNOR, BY MESNE ASSIGNMENTS, TO THE LAMSON COMPANY, A CORPORATION OF MASSACHUSETTS.

SPACING DEVICE FOR PNEUMATIC DISPATCH SYSTEMS.

Original application filed March 26, 1920, Serial No. 369,084. Renewed March 9, 1925. Divided and this application filed March 11, 1925. Serial No. 14,692.

This invention pertains to conveyor apparatus and more particularly to means for spacing articles moving in succession along a predetermined path, the present application being a division of my pending application Serial No. 369,084 filed March 26, 1920, renewed March 9, 1925.

The principal object of the invention is to provide a spacing device of simple character operable by each article of a series temporarily to stop the next successive article. Such an arrangement is especially useful in conjunction with switch or deflector means for diverting articles from their normal path as the device of the present invention provides the necessary interval for resetting the switch or other diverting means after each operation thus preventing the diverting means from becoming jammed by a second article closely following the first.

The invention is herein illustrated by way of example as embodied in a pneumatic dispatch system wherein carriers are propelled through a tube by air pressure but in its broader aspects pertains to conveyor systems in general in which articles move successively along a predetermined path.

In the accompanying drawings Fig. 1 is a fragmentary vertical diametral section through a pneumatic transmission tube showing a preferred form of the invention as interposed between aligned sections of such tube, and

Fig. 2 is a similar view illustrating a modified form of the invention.

Referring to the drawings and particularly to Fig. 1 the numerals 1 and 2 indicate separated aligned sections of a pneumatic transmission tube. A casing 3 is interposed between these sections, such casing being of generally tubular construction and provided with means, for example flanges 4 and 5, for connecting its opposite ends to the tube sections 1 and 2.

This tubular casing thus provides a chamber or passage 6 aligned with the tube sections 1 and 2 and adapted to guide carriers from one section to the other. The casing 3 is provided with a lateral offset 7 at one side providing a recess 8 for a purpose herein-after described.

The casing is also provided with an offset

portion 9 substantially opposite to the offset 7 furnishing a second recess 10 adapted to house a stop lever 11.

This stop lever is preferably, though not necessarily, of unitary construction and comprises spaced ears 12 pivotally secured by means of pins 13 to the opposite walls of the casing. This lever is provided with a head or stop element 14 preferably curved on an arc about the axis defined by pins 13 as a center. The lever 11 also comprises an actuating portion 15 preferably substantially straight and normally extending in an inclined direction transversely of the passage 6. Preferably the weight of the lever 11 is so disposed that its center of gravity lies to the right of the vertical plane of the pivot pins 13.

The upper part of the recess 10 is furnished with a buffer 16 of suitable material, for example felt, against which the upper part of the stop lever normally rests. A second buffer or cushion 17 is arranged at the lower part of the recess 10 for engagement by lower end 15 of the stop lever when the latter is in operative position.

The operation of this device is substantially as follows the parts being normally in the full lined position of Fig. 1:

When a carrier C enters the casing through the tube section 1 its advancing end freely passes the edge of the stop member 14 and eventually engages the inclined arm 15 of the stop lever. This arm immediately swings substantially into the dotted line position of Fig. 1 and its upper end 14 engages the upper or following end of the carrier and thrusts the latter over into the recess 8 thus providing an angular space S just below the lower end of the next advancing carrier C² for the reception of the stop member 14. As the stop member 14 enters the space S it blocks further movement of the next carrier C² while the first carrier C is permitted freely to drop through the passage 6 and into the upper end of the tube section 2.

As soon as the first carrier disengages the stop lever 11, the weight of the latter tends to restore it to its normal position and this action is assisted by the weight of the following carrier C². The point of contact

of the carrier C^2 with part 14 is to the right, as viewed in Fig. 1 of the pivotal axis 13 of the lever so that the weight of the carrier also tends to restore the lever to normal position. The stop lever is thus returned to its initial position and permits the next succeeding carrier to drop to the position of the carrier C in Fig. 1, the above described operation being repeated for each subsequent carrier.

Referring to Fig. 2 a modified arrangement is disclosed in which the tube sections 1^a and 2^a correspond to the tube sections above described. A tubular casing 3^a connects the sections 1^a and 2^a, such casing being furnished with flanges 4^a and 5^a for the reception of said ends of the said tube sections. The interior of the casing furnishes a passage 6^a for carriers on their way from one tube section to the other.

The casing 3^a is furnished with a lateral offset providing a recess 8^a and at its opposite side the casing is provided with a vertical slot 18 and with outstanding ears 19 at either side of said slot. The ears 19 furnish bearings for a shaft 20 provided with a series of radially outstanding arms 21, 22, 23 etc., adapted to project inwardly through the slot 18 of the casing. A plate 24 is secured to the shaft and toggle arms 25 and 26 are hinged at diametrically opposite points to said plate. These toggle arms 25 and 26 are provided with weights 27 and 28 at their outer ends and are connected by toggle links not shown to a friction plate 29 sliding freely upon the shaft 20. An abutment member 30 is supported by one of the arms 19 in a position for engagement by the friction plate as the latter moves along the shaft. The friction plate with the toggle arms and weights furnishes a brake, of the type commonly used in phonographs, for controlling the speed of rotation of the shaft 20.

The operation of this form of the device is as follows: it being assumed that the arm 21 is on the point of leaving the slot 18 and that the arm 22 occupies the position shown in Fig. 2, projecting into the casing through the upper part of the slot. When a carrier, for example that indicated at K in dotted lines in Fig. 2, enters the upper part of the casing it engages the projecting end of the arm 22 and moves said arm downwardly along the slot 18. As the arm 22 approaches the position formerly occupied by the arm 21 the next successive arm 23 will enter the slot 18 and engage the upper end of the carrier throwing such upper end into the position K^a of Fig. 2. The speed of rotation of the arm 22 is controlled by the friction governor device, excessive speed being prevented by contact of the friction disk 29 with the abutment 30.

When a carrier assumes the position shown

at K^a in Fig. 2 it is free to slide down past the end of an arm occupying the position of arm 21, and may thus enter the tube section 2^a, but whenever a carrier has been thrust into the position of that at K^a, the next successive carrier is prevented from following the first carrier too closely by the entrance of another arm through the upper end of the slot. The device thus comprises a spacing and timing mechanism compelling the carriers to move through the tube section 2 at regular intervals apart.

While I have described preferred embodiments of the invention it is to be understood that in its broad aspects the invention is not confined to the specific details herein disclosed but that various changes and modifications both in proportions of parts and arrangements thereof may be made without departing from the spirit of the invention.

I claim:

1. In a conveyor system the combination with means for guiding moving articles in a predetermined path, of means actuatable by the advancing end of an article moving along said path to swing the following end of said article laterally of said path whereby to provide a recess at one side of said following end for the entry of a stop element and simultaneously to release said advancing end for continued movement along the predetermined path.

2. In combination with a pneumatic conveyor system having a guideway for carriers, said guideway having a lateral closed recess adapted partially to receive a carrier therein, means actuatable by the advancing end of a carrier moving along said guideway for pushing the following end of the carrier laterally into the recess.

3. In combination with a pneumatic conveyor system having spaced tube sections, a casing connecting the ends of said sections, said casing having a carrier passage therethrough, a recess being provided at one side of the passage adapted partially to receive a carrier therein, and means actuatable by the advancing end of a carrier moving along said passage for pushing the following end of the carrier laterally into said recess.

4. Carrier spacing apparatus for a pneumatic dispatch system comprising a casing providing a passage for carriers and a recess opening from one side of the passage adapted partially to receive a carrier therein, and means comprising a swinging arm engageable with the advancing end of a carrier moving through the passage, and a second arm engageable with the following end of said carrier for swinging the latter laterally into the recess.

5. Carrier spacing apparatus for a pneumatic dispatch system comprising a casing providing a passage for carriers, and means movable by the advancing end of one car-

- rier of a series moving through said passage to advance a stop in the path of the advancing end of the next carrier of the series, the advancing stop pushing the following end 5 of the first carrier into a recess in the casing to one side of the passage proper and simultaneously retracting the means engaged by the advancing end of the carrier, thereby to permit continued movement of the carrier 10 through the passage.
6. Carrier spacing apparatus for a pneumatic dispatch system comprising means movable by one carrier of a series to advance a stop into the path of the next carrier, said 15 stop tending to move out of said path under the weight of said next carrier.
7. Carrier spacing apparatus for a pneumatic dispatch system comprising a casing providing a passage for carriers, said casing 20 having a recess at one side, and a lever pivoted upon an axis extending transversely of the passage, said lever comprising a stop arm and an actuating arm, the lever being so designed that when in normal position 25 its stop arm is out of the passage and housed in the recess and when in operative position with the stop arm in said passage, the actuating arm is retracted, thereby to permit continued movement of the carrier.
8. Carrier spacing apparatus for a pneumatic dispatch system comprising a casing providing a passage for carriers, said casing having recesses at opposite sides of the 30 passage, a stop member normally housed in one of said recesses, an actuating member normally disposed across the passage and engageable by the advancing end of a carrier to move the stop member into the passage, the advancing end of the stop member pushing the following end of the carrier over into the other recess and simultaneously retracting the actuating member 35

thereby to permit continued movement of the carrier.

9. Carrier spacing apparatus comprising 45 a unitary lever movable by one carrier of a series to check a following carrier, said lever having a stop arm of arcuate curvature.

10. Carrier spacing apparatus comprising 50 a unitary stop lever having an actuating arm engageable by the advancing end of one carrier of a series and a stop arm engageable with the advancing end of the carrier, said stop arm being curved in an arc concentric with the fulcrum point of the lever. 55

11. Carrier spacing apparatus for a pneumatic dispatch system comprising a lever having an actuating arm movable by one carrier of a series to advance a second or stop arm into the path of the next carrier, 60 and a fulcrum for said lever, the center of gravity of the lever and the point of engagement of its stop arm with the next carrier of the series being disposed upon the same side of the vertical plane of its fulcrum. 65

12. Carrier spacing apparatus comprising a casing providing a passage for carriers, said casing having recesses at opposite sides of the passage, a lever pivoted upon an axis 70 extending transversely across the passage, said lever having a stop arm normally housed in one recess and an actuating arm normally extending into the passage, the engagement of the advancing end of one 75 carrier of a series with said actuating arm swinging the stop arm out of its recess and the actuating arm into the same recess, the advance of the stop arm swinging the following end of said carrier into the other 80 recess.

Signed by me at Syracuse, New York, this 28th day of February, 1925.

JAMES G. MACLAREN.
